UNITED STATES PATENT OFFICE

FRANK J. SONHEIM, OF CHICAGO, ILLINOIS

AUTOMATIC WEATHER STRIP

Application filed May 27, 1929. Serial No. 366,187.

The present invention relates to weather strips for windows and has for its main object the provision of a device which would automatically close for preventing rain entering the dwelling and which may automatically open with the opening of the window.

With the above general object in view and others that will appear as the nature of the invention is better understood the same consists in the novel construction, combination and arrangement of parts hereinafter more fully described, illustrated in the accompanying drawing and pointed out in the appended claims.

15 In the drawing forming a part of this application, and in which like designating characters refer to corresponding parts throughout the several views,

Fig. 1 is a cross-sectional view, on horizontal plane, through the window;

Fig. 2 is a cross-sectional view on vertical plane through the window, the view having been taken on line 2—2 of Fig. 1, showing the present device in a closed position;

25 Fig. 3 is a similar view showing the operation of the device when the window is in the process of opening; and

Fig. 4 is a perspective view of a plate associated with the window by means of which 30 the weather strip may be closed.

Referring in detail to the present drawing there is shown therein wall 10 with the usual window frame 11, including sill 12 set therewithin, with inside casing 13.

35 The present invention is adapted to work with so-called French or casement windows, which includes upright sash bars 14, one of which is hinged to the one upright section of the frame 11 by means of hinges 15. Said 40 casement frame further includes horizontal lower sash bar 16, and window pane 17 set within the casement frame.

The present invention includes an angle plate 18, the horizontal portion of which is 45 rigidly mounted upon the sill by means of screws 19, while the upright portion of said angle plate 18 is adapted to remain in abutment with the adjacent face of said horizontal sash bar 16 when the casement frame is in a 50 closed position illustrated on Fig. 2.

The weather strip further includes a stationary longitudinal plate, including the vertical portion 20 by means of which said stationary plate is mounted adjacent the upper end of the window sash bar 16 by means of screws 21. The lower portion of said stationary plate is bent outwardly or away from the window sash bar 16, obliquely as at 22, and then vertically as at 23, then at right angle on horizontal plane towards the window sash bar 16 as at 24, then upwardly as at 25, it being understood that said last mentioned portion 25 remains away from the window sash bar 16. Thus, it will be seen that said lower portion of said stationary plate assumes a J-shaped formation on vertical cross-section, as clearly seen on Figs. 2 and 3.

55 The weather strip further includes movable guard plate 26, likewise being J-shaped on cross section, which is adapted, by its bent or upper end to engage the lower bent end of said stationary plate. Thus, the bent ends of the two plates form a longitudinal joint.

60 Said movable guard plate 26 is adapted to assume two positions, each shown on Figs. 2 and 3, one closed position and the other open position, respectively.

65 Below the vertical portion 20 of the stationary plate of the weather strip there is a spring plate 27 affixed by its upper end to the window sash bar 16 by means of screws 28, while the lower edge of said spring plate 27 is bent away from the window sash bar 16, 70 said spring plate 27 being of a resilient nature so that its lower edge is adapted to contact with and exert the pressure at the movable guard plate 26 at the back thereof or at its face nearer to the window sash bar 16, for 75 the purpose of holding the same in closed position shown on Fig. 2 or in its open position illustrated on Fig. 3.

80 It is to be understood that said angle plate 18, the stationary weather strip, the movable guard plate 26 and spring plate 27 are all lengthwise disposed of the window sash bar 16 and extend from one upright portion of the window frame 11 to the opposite one.

85 The device further includes a short angle 90

plate 29, best shown on Fig. 4, which includes portion 30 having apertures 31 for passing screws 32 by means of which said plate 29 is rigidly mounted upon the inner face of one of the upright bars of the window frame 11. In the operative position of angle plate 29, the free portion 33 thereof extends within the window and remains in an oblique position with respect to the horizontal and vertical portions of the angle plate 18.

When the casement frame is closed within the window frame, as seen on Fig. 2, the lower free end of the movable guard plate 26 is in an upright position and overhangs the vertical portion of angle plate 18, or more specifically is disposed outwardly of the free face of said upright portion of angle plate 18. Thus, any rain drops will ride upon the outer face of stationary plate of the weather strip and of the movable guard plate 26, falling upon the horizontal portion of the angle plate 18. None of them will be permitted to enter past said upright portion of the angle plate 18 and towards the juncture between the window sill 12 and horizontal window sash bar 16 when the latter is in a closed position within the window frame 11 shown on Fig. 2.

When the casement frame is opened within the dwelling, as seen by dotted lines on Fig. 1, upon its hinges 15, the face of the free lower end of the movable guard plate 26, which is adjacent the window sash bar 16, will be caused to ride upon the upper edge of the upright portion of the angle plate 18, which process will cause the opening of said movable guard plate 26, the upper bent end of said movable guard plate 26 will revolve around its joint with the bent lower end of stationary plate to assume the position shown on Fig. 3. The action of the free or lower edge of spring plate 27 exerting pressure at the adjacent face of said movable guard plate 26 will maintain said movable guard plate 26 in either closed or open position as already mentioned.

When the casement frame is closed the lower end of the movable guard plate 26 will hit the free portion 33 of short angle plate 29 and will ride thereupon until the casement frame is completely closed within the window frame and said free end of movable guard plate 26 assumes the vertical or closed position shown on Fig. 2. In assuming this position said movable guard plate 26 is held by the pressure exerted thereupon by the spring plate 27 as well as by the tendency of said movable guard plate 26 to seek most suitable position within the joint made by the bent end thereof with the bent end of said stationary plate.

It is to be understood that the weather strip herein disclosed may also be adapted for use in connection with doors.

While there is described herein a preferred embodiment of the present invention it is nevertheless to be understood that minor

changes may be made therein without departing from the spirit and scope of the invention as claimed.

What I claim as new is:

1. In a window having a sill and a horizontal sash bar, a weather strip comprising an angle plate, the horizontal portion of said angle plate being mounted upon said sill and the upright portion thereof being adapted to contact with the face of said sash bar when the sash is in a closed position, a stationary plate mounted by its upper end to said sash bar, the lower end thereof flaring out and terminating in a bend towards said sash bar, a movable guard plate, the upper end of said movable guard plate having a bend away from said sash bar whereby said movable guard plate engages said stationary plate, the bends in said stationary plate and in said movable guard plate having angular formation on transverse cross-section, said bends constituting a joint for the two plates, a spring plate mounted upon said sash bar, said movable guard plate is adapted to assume vertical closed or horizontal open positions, said spring plate being adapted to contact with the adjacent face of said movable guard plate for maintaining the same in either position, said movable guard plate is adapted to overlie the upright portion of said angle plate, the upper edge of the upright portion of said angle plate being adapted to contact with the adjacent face of said movable guard plate and to ride thereupon when the window is in the process of opening for the purpose of shifting said movable guard plate into a horizontal open position, and means for engaging said movable guard plate during the process of closing of the window for the purpose of bringing said movable guard plate into an upright closed position.

2. In a window having a sill and a horizontal sash bar, a weather strip comprising an angle plate mounted upon said sill, a movable guard plate upon said sash bar, said guard plate being adapted to assume horizontal open or vertical closed positions, resilient means for maintaining said guard plate in either position, said movable guard plate being adapted to open and assume horizontal position during the opening of the window by virtue of the engagement of said movable guard plate with said angle plate and its ride thereupon, and means for shifting said movable guard plate into a vertical closed position during the process of closing the window.

In testimony whereof I affix my signature.

FRANK J. SONHEIM.
